UNITED STATES PATENT OFFICE.

EMIL H. HABICK, OF EUCLID, MINNESOTA.

MOWER ATTACHMENT FOR CARS.

1,106,650.

Specification of Letters Patent. Patented Aug. 11, 1914.

Application filed May 13, 1913. Serial No. 767,478.

To all whom it may concern:

Be it known that I, EMIL H. HABICK, a citizen of the United States, residing at Euclid, in the county of Polk and State of Minnesota, have invented certain new and useful Improvements in Mower Attachments for Cars, of which the following is a specification.

This invention relates to an improvement 10 in mowing machines.

The primary object of the invention is to provide a mowing machine adapted to be supported on a railway car truck and including cutting mechanisms disposed at both 15 sides of the truck which may be adjusted with respect to the truck and which may be independently driven by means arranged on the truck.

A further object of the invention is to 20 provide a driving mechanism supported on the platform of a truck which will propel the truck and which will operate the cutting mechanisms, the cutting mechanisms being capable of operation either together or independently.

A still further object of the invention is 25 to provide a supporting structure for the cutting mechanism at each side of the platform which may be raised and lowered by means operable from the platform and which, when the cutting mechanism is in use, will effectually support the same.

Another object of the invention is to provide a driving mechanism for the cutter at 30 each side of the platform and in which the main driving shaft will form a support for the cutting mechanism.

For a full understanding of the invention, 35 reference is to be had to the following description and accompanying drawings, in which:—

Figure 1 is a rear elevation; and Fig. 2 is a top plan view.

Corresponding and like parts are referred 40 to in the following description and indicated in all the views of the accompanying drawings by the same reference characters.

In the drawings, 10 designates a wheeled support. A platform 11 is mounted on this support, said platform being provided with bearings 12 which embrace the axles 13 of the support. Arranged on the platform is a motor 14, which may be of any suitable construction, said motor driving a shaft 15. A 50 shaft 16 is disposed at right angles to the

shaft 15, there being a gear 17 mounted on said shaft which meshes with a gear 18 mounted on the shaft 15. A sprocket 19 is also mounted on this shaft, the sprocket chain 20 passing over this sprocket and 60 sprocket 21 mounted on one of the axles 13 to drive said axle. The sprocket 19 is loosely mounted on the shaft 16, there being a sliding clutch member 22 arranged on said shaft and adapted to lock the sprocket thereto when it is desired to drive the axle 13. Shafts 23 and 24 are mounted within bearings 25, these shafts being in axial alignment with the shaft 16 and disposed on each side of the same, their terminals projecting 65 beyond the sides of the platform. Clutch members 26 are disposed on each of the shafts 23 and 24, said clutch members engaging clutch members 27 which are arranged on the terminals of the shaft 16. It 70 will be noted that by this construction either of the shafts 23 or 24 may be driven by the shaft 16. A gear 28 is arranged on the terminal of each of the shafts 23 and 24. A plurality of brackets 29 are supported on 75 each side of the platform 11, there being a bracket disposed adjacent each end of the platform and one intermediate the ends. These brackets support a shaft 30, there being a gear 31 arranged on each of these 80 shafts 30 which meshes with the gear 28.

A frame 32 is hingedly mounted on the shaft 30, this frame consisting of the longitudinal beam 33, the terminals of which are offset, the terminal 34 of the beam receiving 90 the shaft 30 adjacent one of its terminals and beyond one of the end brackets 29. The shaft is terminally provided with an enlargement 35 which contacts with the terminal of the beam 33. A transverse bar 36 is 95 secured to the terminal 37 of the beam 33, said bar at its end remote from the beam being formed with a bearing 38 which receives the shaft 30. A bracket 39 is mounted on this bar, the terminal 40 of this bracket being secured to the bar by bolts which pass through the terminal of the beam 33. The outer terminals of the bar 36 and bracket 39 are hingedly connected, as at 42, with the cutting mechanism 43. This hinge connection may be of any well known type, and is, therefore, only conventionally illustrated in the drawings inasmuch as the specific form of the connection does not constitute any part of this invention. While this cutting 105

55 shaft 16 is disposed at right angles to the

mechanism is not illustrated in detail, it is to be understood that the same is of the usual construction, including a supporting beam and a reciprocating cutter bar. This cutter bar 44 is actuated by the rod 45, the rod having a connection with the cutter bar whereby the cutting mechanism may be swung freely with respect to the rod and the frame 32. The rod 45 is driven by the disk 46 mounted on the terminal of the shaft 30. A substantially L-shaped brace 47 has one of its terminals 48 connected to the transverse bar 36. This brace 47 is connected adjacent its arm 49 with the beam 33. The arm 49 of the brace extends parallel with the bar 36 and is terminally provided with a bearing 50 which receives the shaft 30. A brace 51 is connected to the beam 33 adjacent its terminal which is mounted on the shaft 30, the other end of said brace being connected to the arm 49 of the brace 47 intermediate its ends. Particular attention is called to the construction of this frame and the manner in which the same is mounted on the shaft 30. It has been found in practice that in machines of this character the cutting mechanism, which must be adjustable when in operation, must be effectually supported and the driving means for the same so mounted as to operate the cutting mechanism regardless of the angle at which it is disposed. The present structure is devised to effectually support the cutting mechanism in such a manner with respect to the wheeled support that it will be maintained rigid at all times and at right angles to the line of travel of the wheeled support. It will be seen that the frame 33 is hingedly mounted with respect to the support, and that the driving shaft for the cutting mechanism forms a support for the frame, this peculiar arrangement eliminating numerous parts which are necessary when the frame is mounted directly on the platform.

A mast 52 is arranged on each side of the platform, said masts projecting obliquely from the platform and being provided at their terminals with sheaves 53 over which the cables 54 pass. The cables 54 are each connected to the outer end of the cutting mechanism 43 and when actuated adjust said cutting mechanism with respect to the frame 32. The cable which passes over the sheave of the mast at one side of the platform is wound upon a drum 55 supported by the standard 56 adjacent the side of the platform remote from said mast. There are two of the standards 56, one being arranged at each side of the platform, each standard at its upper end supporting a drum 55 and at a point below said drum a second drum 57. Cables 58 are secured to the drums 57 and disposed to be wound thereon, the cables 58 each being connected to a ring 59 secured adjacent the upper terminal of one of the

masts 52. A beam 60 is secured to the mast adjacent its sheave supporting terminal, said beam 60 being connected adjacent the cutting mechanism to the frame 32.

The masts 52 are hingedly mounted on the platform and when the cables 58 are wound upon the drums 57, the frame 32 will be lifted by means of the beam 60. Thus the cutting mechanism may be raised by means of the cable 54 to assume a position parallel with the beam 60, and then the frame 32 raised by means of the cable 58. By this construction, it will be noted that the cutting mechanism may be adjusted to various heights, and that when the same is not in use it may be lifted to a point where it may clear obstructions along the track.

Particular attention is called to the manner in which the frame and the cutting mechanism are supported with respect to the platform, and to the fact that the frame may be adjusted to dispose the cutting mechanism at various heights. The frame 32 on one side of the platform is oppositely disposed to that on the other side of the platform, the cutting mechanism, while operating in the same direction, being arranged in staggered relation.

The many advantages of a construction of this character will be clearly apparent, as it will be noted that the machine provides an effectual cutting mechanism for cutting weeds and grass adjacent railway tracks, and particular attention is directed to the simple manner in which the cutting mechanisms are actuated and adjusted. It will be seen that the entire structure is such as may be easily and economically manufactured, and that the various parts may be readily assembled.

What I claim is:—

1. In a device of the character described, a wheeled truck, supporting frames pivoted to the sides thereof, a cutting mechanism pivoted to each of the frames, actuating means carried by the truck and connected to the cutting mechanism for operating the same, a mast swingingly attached to each side of the truck, a beam connecting the upper terminal of each mast with the outer terminal of the adjacent frame, a pulley journaled in the upper terminal of each mast, a pair of cables freely connected to the masts at the junction of the beams therewith, a cable for each cutting mechanism, said cables being freely connected to the outer terminals thereof and being directed over the pulleys of the masts, and independent winding drums for each of the said cables whereby either cutting mechanism may be independently adjusted with respect to the frame to which it is attached or whereby either frame may be adjusted independently of the cutting mechanism which it carries.

2. In a device of the character described, a wheeled platform, frames pivoted to the

sides thereof, a mast pivoted adjacent the frames, beams connecting the outer terminals of the frames and the upper terminal of the adjacent mast, a pair of cables connected to the masts, independent winding drums for the cables whereby either mast may be independently adjusted with respect to the platform, a cutting mechanism pivotally connected to the outer terminal of each 10 of said frames, a pulley journaled at the upper terminal of each of said masts, a cable connected to the outer terminal of each of the cutting mechanisms, said last-mentioned

cables being directed over the pulleys of the masts, and independent winding drums 15 mounted on the platform and receiving the last-mentioned cables whereby either cutting mechanism may be independently adjusted with respect to the frame to which it is attached.

In testimony whereof I affix my signature in presence of two witnesses.

MR. EMIL H. HABICK.
